UNITED STATES PATENT OFFICE.

JAMES DYCHE, OF STAFFORD, ENGLAND.

HEEL.

1,101,066.

Specification of Letters Patent.

Patented June 23, 1914.

Application filed November 29, 1913. Serial No. 803,729.

To all whom it may concern:

Be it known that I, JAMES DYCHE, subject of the King of Great Britain, residing at Telon Works, Stafford, in the county of Stafford, England, have invented certain new and useful Improvements in Heels; and I do hereby declare that the following is a full, clear, and exact description of the same.

10 My invention comprises improvements in the constructions of heels for boots, shoes and the like and refers to that class of such which are manufactured from wood.

It is well known that this type of heel is very liable to split both in manufacture and in use and prior to this invention it has been proposed to introduce into the heel a thin strip of wood or insertion having the grain in the opposite direction or 20 at right angles to the grain of the heel proper, but in such case the inserted strip was visible at the side of the heel, being unsightly in use, particularly after the heel has become wet, when the inserted piece is liable to swell.

The object of the present invention is to overcome these defects and to provide an improved heel, in which the inserted piece is invisible when the heel is in use.

30 According to this invention the heel is provided with a slot or opening extending rearwardly for the greater part of the length of the heel from the front face of the heel but without extending to the sides of the heel and into this opening an insertion of wood with the grain arranged at right angles to the heel proper or a piece of leather or other suitable material is placed, being glued under pressure or otherwise secured in position.

Referring to the drawings:—Figure 1 is a perspective view of a heel according to this invention. Fig. 2 is a longitudinal section of same. Fig. 3 is a transverse section. Fig. 4 illustrates the insertion plate removed.

In carrying my invention into practice as illustrated upon the accompanying draw-

ings the heel *a* is formed with a recess or slotted opening *a*¹ extending from the front face *a*² of the heel and of a size and shape corresponding with that of the insertion piece which is illustrated at Fig. 4. This recess may be conveniently formed by a rotating cutter of corresponding size but in such case it is necessary to either first cut away the opening *a*³ to receive the axle carrying the cutter or to provide a second cutter of smaller diameter which cuts the opening *a*³ simultaneously with the recess *a*¹.
The insertion piece shown at Fig. 4 may be of a single piece of wood having the grain arranged transversely, *i. e.* at right angles to the grain of the main heel *a*, or it might be of three ply wood or of leather or of other suitable material. The insertion piece *b* is placed in the recess *a*¹ which it exactly fits being there glued under pressure or otherwise secured, the insertion piece being of a sufficient width to receive the usual securing nails or screws. The opening *a*³ is suitably filled in.

What I claim is:—

In a shoe heel, the combination of a wooden body member having a recess extending into the heel from the front face thereof and lying at a short distance below the surface, said recess being of sufficient size to receive all of the nails employed in fixing the heel to the shoe upper, but not extending completely to the sides or rear of the heel, and an insertion piece adapted to be inserted in said recess and secured therein by suitable adhesive for the purpose of strengthening the wooden body in a direction transversely to the grain of the wood therein and to prevent the splitting of said heel when being nailed to the upper.

In testimony whereof I have signed my name to this specification in the presence of two subscribing witnesses.

JAMES DYCHE.
